UNITED STATES PATENT OFFICE.

JOHN CLELLAN HALE, OF ALEXANDRIA, SCOTLAND, ASSIGNOR TO RUDOLPH MEIER HOWISON, OF LONDON, ENGLAND.

HEEL FOR BOOTS OR SHOES.

SPECIFICATION forming part of Letters Patent No. 740,124, dated September 29, 1903.

Application filed April 1, 1903. Serial No. 150,524. (No model.)

To all whom it may concern:

Be it known that I, JOHN CLELLAN HALE, a subject of the King of Great Britain and Ireland, residing in Alexandria, Scotland, have 5 invented certain new and useful Improvements in Heels for Boots or Shoes, of which the following is a specification.

This invention relates to an improved heel for boots and shoes; and it has for its object 10 to construct a composite heel of leather and rubber in such a manner as to avoid the disadvantages attending the employment of heels of this class. With these heels as at present constructed it is found that there is 15 considerable difficulty in securing and maintaining a perfect and complete contact between the outer surface of the heel of the boot and the inner face of the supplementary heel. Not only does the aforesaid disadvantage 20 arise when applying the supplementary heel to a new boot, and consequently when the surface of the heel is more or less flat, but when the heel is applied to an old or worn surface the disadvantage is increased to such 25 an extent as to leave open spaces between the respective parts, which permit the heel to engage with any projection or unevenness of the ground, causing the wearer to trip, and the heel thus becomes a source of danger in- 30 stead of a protective device. This, in addition to reducing the utility of such heels, per- 35 mits the entry between the surfaces of dirt or other foreign matter, which destroys the material and further causes discomfort to the wearer. Further, although an approximately 40 perfect contact is established between the respective surfaces when new, yet under the wear it is found that the heels have a gradually-increasing tendency to curl up, leaving the boot-heel proper at the outer edges.

It is the object of the present invention to construct a heel of this class in such a manner as to avoid the aforesaid disadvantages by insuring close, firm, and permanent con- 45 tact between the whole of the respective sur- faces of the heel and the boot whether the latter be new or worn.

The improved heel consists of a flat piece of rubber or other elastic or comparatively 50 elastic material of an outline conforming more or less to the outline of the surface to

which it is to be applied. The rubber or the like is perforated or recessed and is backed with canvas or other like material, the object of which is to limit the expansion of the rubber plate upon the under side. In the opening or cavity is tightly fitted a piece of leather or other substance. The dimensions of the leather being necessarily somewhat in excess of the dimensions of the cavity destined to receive it when in position, the leather exerts a side pressure in all directions, which causes the surrounding material to curve or belly outward. Under these circumstances the surfaces of the heel with the leather in position instead of being flat are respectively con- 65 cave and convex, the concave surface being that presented to the boot-heel.

It is evident that if the boot-heel, as above described, be pressed down upon a flat sur- 70 face the marginal edges thereof will first come into contact with the said flat surface, the area of contact increasing as the composite heel is forced against the boot-heel until even- 75 tually the two surfaces are pressed together and maintained in close and firm contact. By this means not only is the heel much firmer under the wearer's weight, but the entry of foreign matter in the manner previously re- 80 ferred to is prevented and the life of the heel considerably increased.

In order that the invention may be the bet- 85 ter understood, drawings are appended, in which—

Figures 1 and 2 illustrate the component 85 members of a heel. Fig. 3 is a side elevation of the central portion thereof. Fig. 4 is a sec- 90 tional view showing the central portion of the heel ready for insertion in its retaining cavity or recess. Fig. 5 is a sectional view illustrat- 95 ing the action of the central portion of the heel. Fig. 6 is a view showing the general appearance of the heel with the central por- 100 tion in place.

Referring to the drawings, Figs. 1 to 6, a 95 represents a plate of rubber perforated at b and provided with a backing of canvas or other material c.

d is a piece of leather conforming in outline to the outline of the cavity in the leather, but 100 of somewhat greater dimensions, as clearly shown in Fig. 4. The walls of the cavity in

the instance referred to are square with the surface of the rubber, as are also the edges of the leather *d*. It is obvious that if the leather *d* be placed in the cavity in the rubber the 5 softer material will yield in all directions. By this means the area of the outer surface of the rubber will be increased relatively to that of its under surface, the expansion of which is prevented by the canvas backing, 10 and consequently it will assume a curved or bellied shape, which will increase as the leather is forced home until approximately that illustrated in Fig. 5. In the figure referred to the heel is shown as applied to the 15 outer surface of a boot-heel *e*, to which it is secured by means of nails or the like, *f*, driven through the leather center, as shown in Fig. 6.

When placing the central leather plate in position in order to insure its proper and complete introduction into the recess, so that the 20 under surface of the said plate bears against the canvas backing forming the bottom of the recess, I first place the aforesaid central disk within the recess and push same home 25 as far as it will go. It will be found that whatever the direct pressure exerted upon the central plate when such pressure is reduced there will always be a space left between the backing and the inner face of the 30 central plate. In other words, the disk will not be properly bedded upon the backing. To overcome this, I bend the rubber of the outer plate backward at the point of junction between the edges of the recess and the walls

of the inner plate. This not only permits the 35 central disk to be bedded upon the backing, but also when the rubber is permitted to assume its normal position the said central plate will be prevented from displacement, and when the heel is nailed in position an 40 effective and permanent contact will be established between the whole of the surfaces irrespective of the fact that the boot-heel proper may have been considerably worn before the outer heel was applied. 45

Having thus described my invention, I claim—

1. A boot-heel of the kind specified, comprising a plate of elastic material having a central opening, a backing of fabric secured 50 to said plate and forming a bottom for said opening, and a plate of leather of larger dimensions than said opening and adapted to be placed thereinto.

2. A boot-heel of the kind specified, comprising a plate of rubber having a central opening, a backing of fabric secured to said plate and forming a bottom for said opening, and a plate of leather of larger dimensions than said opening and adapted to be placed 55 thereinto.

In witness whereof I have hereunto set my hand in the presence of two witnesses.

JOHN CLELLAN HALE.
